UNITED STATES PATENT OFFICE

LOUIS H. MORIN, OF NEW YORK, N. Y., ASSIGNOR TO UNITED STATES ENVELOPE COMPANY, OF SPRINGFIELD, MASSACHUSETTS, A CORPORATION OF MAINE

CUP VENDING MACHINE

Original application filed July 31, 1929, Serial No. 382,359. Divided and this application filed May 8, 1930. Serial No. 450,707.

This invention relates to check-controlled or coin-controlled service-supplying devices or automatic sales devices, as used for example in the vending of paper cups,—the 5 present application being a division of my copending application Serial No. 382,359 filed July 31, 1929, for cup vending machines.

It is well known to those versed in the art relating to check controlled or coin controlled service-supplying devices or automatic sales devices, including vending machines, that the constructional features, and consequently their cooperating relation and manner of operation, throughout the entire 10 operating mechanism, commonly from a movable operating handle to a final delivery member or other service-supplying member or part, is largely determined by, and must necessarily be different or varied in accordance with, the nature of the service to be provided or the kind of articles to be vended. While the vending machine of the present invention was invented and is particularly constructed and designed for the vending of 15 paper drinking cups of a certain kind, it is of course to be understood that various features thereof might be to a greater or less extent changed or modified while still performing substantially the same final function or result, as well as also for adapting the 20 machine to render a more or less different kind of service.

One of the objects of the invention is to provide a vending machine which will effectively render the service above noted. Other 25 objects of the invention are reliability, simplicity, strength, durability, convenience in use and facility of manufacture. Other objects and advantages will hereinafter appear.

The invention includes various features of construction and combinations of parts, as 30 will appear from the following description.

The embodiment of the invention illustrated in the accompanying drawings will now 35 be particularly described and thereafter the invention will be pointed out in claims, reference now being had to the drawings, in which:

Fig. 1 is a reduced front elevation of a 40 vending machine embodying the invention;

Fig. 2 is a vertical section substantially on the zig-zag line 2—2 of Fig. 3, the upper portion of the container tube or magazine being broken away;

Fig. 3 is a similar section taken substantially on the line 3—3 of Fig. 2; 55

Fig. 4 is a partial horizontal section on the line 4—4 of Fig. 3 as viewed from below;

Fig. 5 is a horizontal section just above the top of the machine casing taken on the 60 line 5—5 of Fig. 3;

Fig. 6 is a horizontal section taken as to its upper half substantially on the zig-zag line 6—6 and as to its lower half taken substantially on the line 6a—6a of Fig. 3; 65

Fig. 7 is for the most part a substantially central vertical section taken on the zig-zag line 7—7 of Fig. 3;

Fig. 8 is a partial horizontal section with some of the operating parts omitted taken 70 substantially on the line 8—8 of Fig. 3;

Fig. 9 is a partial vertical section as viewed from the rear of the machine and with parts omitted taken substantially on the zig-zag line 9—9 of Fig. 3; 75

Fig. 10 is a partial rear elevation of a rocking operating member which comprises a gear segment, a cam and a ratchet;

Fig. 11 is a transverse section taken on the inclined line 11—11 of Fig. 10 as viewed at 80 right angles to this line from below.

Like reference characters refer to like parts in the different figures.

A stack of the nested cups 1, forming a supply to be vended, is contained in an upright magazine tube 2, which may be a steel stamping, seamed together. The upper end of this tube is closed by a cap 3 secured thereon which may be a drawn steel shell. The container tube 2 is shown as of octagonal 85 cross section elongated from front to rear in conformity with the transverse elliptical shape of the stack of nested cups 1 (Fig. 5), which is contained loosely therein for free downward gravitational movement. The 90 cups 1 in this stack are in their upright position with their bottoms down. The lower end of the magazine tube 2 opens freely downward into the top of a multi-part casting which is open at its lower or bottom end, 95 100

and the principal parts of which may be zinc die-castings, this main casing being in general substantially rectangular, as appears in Figs. 5 and 6, and being substantially larger 5 transversely than the magazine tube 2.

The casing comprises a substantially trough-shaped back piece 4 and a substantially similarly shaped front piece 5 which join along their edges at the side and are 10 there firmly secured together by means of dowel pins and screws, some of which appear in the drawings. Similarly firmly secured to the front casing part 5 towards its top and forwardly spaced therefrom by means of 15 rearwardly extending lateral flanges is a front plate 6. A centrally open casing top 7 interlocks at the rear with the inner side of the upper end of the casing back 4 (Fig. 3) and has a front wall which extends forward- 20 ly at a downward inclination and then downwardly to the upper edge of the front plate 6 in alignment therewith. The inclined portion of this front wall is provided with a key-operated lock 8, the bolt 9 of which is en- 25 gageable with an inclined keeper lug 10 (Fig. 2) formed on a bracket 11 shown as secured to the top and front of the front casing part 5 by means of a pair of screws 12.

The lower end of the container tube 2 has 30 a snug fit in the octagonal opening in the casing top 7 (Figs. 2, 3 and 5). The lower end of the container tube 2 for the most part rests upon shoulders formed in the opening of the casing top 7 (Fig. 3) but at its sides 35 the tube 2 is provided with downward extensions or tongues the ends of which are turned outwardly and upwardly to form hooks which engage beneath a downwardly extending inner flange of the casing top 7 (Figs. 40 2 and 3), so that thereby the lower end of the container tube 2 is firmly secured to the casing top 7 within its opening. The casing top 7 together with the magazine tube 2 may be removed from the rest of the casing by un- 45 locking the front lock 8.

The casing is provided with a front door 13 which has rather deep or wide lower and lateral rearwardly extending flanges. The rear edge of the lower flange of this door 13 50 is hinged at 14 to the lower end of the main casing front 5. At the front the door 13 is in alignment with and extends up to the lower edge of the front plate 6. This door 13 may be locked in closed condition by means 55 of a bolt 15 turned over to form a handle at its upper end and passing downward through lugs on the front plate 6 and at its lower end through a lug on the door 13 at the top thereof (Fig. 2). The handle end of this 60 bolt 15 is readily accessible through the open top of the casing when the lock 8 has been unlocked and the casing top 7 removed. If desired a separate lock may be provided for the front door 13 in addition to or in place 65 of the bolt 15. This separate lock is indicated

by the removable plug 16 in the upper edge of the door 13, which may be replaced by a lock similar to the lock 8 and the bolt of which may engage at the back of a keeper lug 17 on the lower edge of the front plate 70 6 (Fig. 3).

The enclosed space at the inner side of this front door 13 forms a coin receptacle or money box at the front of the front casing part 5, into the top of which discharged coins 75 may drop from the coin controlled mechanism, as will hereinafter appear. The front of the magazine tube 2 just above the casing top 7 is provided with a glass window 18 held in place on the tube by means of a frame 19 and is held in this frame by a small removable clip 20 at the inner side of the casing top 7, secured in place by a screw (Figs. 3 and 5).

The stack of cups 1 descends by gravity 85 from the magazine tube 2 through the casing top 7 into the upper portion of the main tubular casing body formed by the casing back piece 4 and the casing front piece 5, with the bottoms of the cups 1 formed by 90 their angular bottom edges foremost or downward. It will be noted that the angular bottom edges of the cups and also the longer diameter of their elliptical upper edges or rims extend from front to rear in the stack 95 of these cups in the machine. The stack of cups is supported, as described in the aforesaid parent application Serial No. 382,359, by suitably mounted rollers 30 and 34, and is subject to the lifting action of fingers 29 and 100 33, on the rock shafts 23 and 32.

Normally the acutely angular straight folded bottom edge or end of the lowermost cup 1 rests lightly upon and in the angle between a pair of similar right and left feed rollers 105 43 and 44 journaled at the proper position on horizontal parallel axes which are parallel with the axes of the rock shafts 23 and 32.

The feed rollers 43 and 44 are pressed on so 110 as to be firmly fixed upon peripherally flanged and shouldered cores 45 and 46, respectively. The same zinc die casting may be used for each of these two cores. The feed rollers 43 and 44 are mounted on their respective cores 45 and 46 in relatively reversed position so 115 that thereby one of these rollers has its terminal circumferential tooth or rib adjacent to the flange on the core while the other feed roller has its circumferential terminal end space adjacent to the flange on its core. The feed rollers 43 and 44 are in vertical alignment with the cup-supporting rollers 30 and 34, and as shown in the drawings (Figs. 3 and 7) the feed roller cores 45 and 46 have 120 their peripherally flanged ends turned towards the rear of the machine casing.

The core part 45 of the right hand feed roller 43 is fixed upon the middle portion of a horizontal shaft 47, such as by means of a set screw 48, and the core part 46 of the left hand 125

feed roller 44 is similarly fixed upon another horizontal shaft 49 at the same level. The right hand feed roller shaft 47 is journaled adjacent to its rear end in the lower part of 5 the right hand frame bracket 21 (Fig. 3) and the forward end of this shaft extends loosely through a large opening in the front wall of the front casing part 5 and has its reduced end journaled in a bearing formed by a lug 10 50 (Figs. 3, 8 and 9) which projects rearwardly from the lower portion of the front plate 6. The left hand feed roller shaft 49 is journaled adjacent to its front and rear ends in horizontal slots 51 in the lower portion 15 15 of the left hand frame bracket 22. At each of these slots, a horizontally slidable bearing pin 52 at the left side of the feed roller shaft 49 is guided in the bracket frame 20 22 and pressed against the feed roller shaft 49 by a coiled thrust spring 53 (Figs. 3 and 7). These springs 53 press the left hand feed roller 44 firmly into cooperating feeding relation with the right hand feed roller 43. The rear ends of the feed roller shafts 47 and 49 25 25 have fixed thereon respectively similar large intermeshing spur gears 53a and 53b by which the two feed rollers 43 and 44 are positively connected together for cooperating rotation at the same rate in opposite directions.

30 A smaller spur gear 54 for operating the feed rollers 43 and 44 is loosely mounted on the right hand feed roller shaft 47 just at the front of the wall of the front casing part 5 and is provided with a hub sleeve 55 extending inward through the opening in this casing wall. This operating gear 54 is connected to the right hand feed roller 43 through a one-way clutch. A clutch sleeve 56 is loosely mounted on the roller shaft 47 between the 35 40 feed roller core 45 and the operating gear sleeve 55 and at its rear end is provided with a clutch head 57 adjacent to the front end of the feed roller core 45. At its rear end the gear sleeve 55 is provided with a square-shouldered diametral rib which seats in a 45 complementary diametral groove in the forward end of the clutch sleeve 56, as shown in dotted lines in Fig. 3, so that thereby the operating gear 54 is positively connected to the clutch sleeve 56 for unitary rotation therewith in either direction. The driving gear 54 and the clutch sleeve 56 may be zinc die-castings, while the two feed roller shafts 47 and 49 may be of brass.

50 The rear face of the clutch head 57 carries a circumferential series of drive studs 58, shown as four in number, which may be cast thereon in the same piece therewith. The drive studs 58 pivotally carry gravity pawls 59 which project therefrom in a counter-clockwise direction (Fig. 7). The free ends of the clutch pawls 59 engage with the teeth of a continuous circular internally toothed ratchet 60 formed on the feed roller core 45, 55 for transmitting counter-clockwise rotation

only from the operating gear 54 to the right hand feed roller 43, while the operating gear 54 is free to rotate idly in the opposite direction, with the feed rollers 43 and 44 at rest. In this way steps of feed movement may be 70 imparted to the feed rollers 43 and 44 intermittently alternating with periods of rest, each such step of feed movement being of sufficient extent for effecting the delivery of the lowermost cup 1 from the bottom of the 75 stack, with a slight overthrow of the feeding movement of the feed rollers in order to assure that the upper edge or rim of the cup has passed completely below and is free from the feed rollers, so this cup may then drop 80 for delivery. Operating means are provided for operating the feed rollers 43 and 44 and the lifting fingers 29 and 33 in proper timed relation as to these feed rollers and 85 lifting fingers.

A rocking operating member 61 is pivotally mounted for to and fro movement at the front of the front wall of the front casing part 5 on a horizontal axis parallel with the axes of the rock shafts 23 and 32 and of 90 the feed roller shafts 47 and 49 and intermediate to these shafts. This operating member 61 is shown as loosely pivotally mounted on a rotatable handle shaft 62, the inner end of which is pivoted in the wall of the 95 front casing part 5 and which extends forwardly through the front plate 6 where its outer end has a handle knob 63 fixed thereon by means of which the entire operating mechanism of the vending machine may be 100 manually operated. In the embodiment of the invention shown in the drawings, the operating member 61 is operated from the handle shaft 62 through the intermediary of coin controlled mechanism. For operation without coin controlled mechanism the operated member 61 may be fixed upon the handle shaft 62, for example by means of a set screw in its hub similar to the set screws 48 for the feed rollers. In such case the coin controlled 105 mechanism may be omitted or it may be present and not used.

The rocking operating member 61 has a general resemblance to a wheel with a peripheral front flange which at the left side through 115 about 130° has a considerably wider portion 64 (Figs. 2, 10 and 11). The right half of this operating member 61 in its normal position (Fig. 2) forms a semi-circular spur gear segment 65 the teeth of which are in 120 engagement with the operating gear 54 for the feed rollers 43 and 44. Throughout its length at the rear the wide flange 64 of the operating member 61 is provided with a cam which faces radially outward and comprises 125 an inner arcuate circumferential initial portion 66, an intermediate radially inclined portion 66a and an outer circumferentially arcuate terminal portion 66b (Figs. 2, 3, 10 and 11). This cam is at all times in engage- 130

ment with the cam roller 28, which is carried by the cam lever 24 on the left hand rock shaft 23.

The exact extent of the forward or clockwise rotation of the rocking operating member 61 from the normal position of rest thereof shown in the drawings is not critical and may be, for example, through 105° or a little more than that, in the relative proportions of the operating parts of the mechanism shown. In its clockwise movement the rocking operating member 61 rotates the feed rollers 43 and 44 through the above described one-way clutch for thereby delivering a single cup 1. The feed rollers are desirably rotated to a slightly greater extent than is absolutely required for delivering the cup in order thereby to make sure that the upper edge or rim of the cup is entirely free from the gripping action of the feed rollers, so it may drop for delivery. Of course the extent of this idle rotation or overthrow of the feed rollers is immaterial. During the return movement or counter-clockwise rotation of the rocking operating member 61, the feed rollers 43 and 44 will be at rest, by reason of the disengagement of the one-way clutch.

Normally the cam roller 28 rests upon the inner or depressed arcuate cam surface 66, for thereby holding the combined supporting and lifting fingers 29 and 33 in position for supporting the stack of cups 1 on the lift finger rollers 30 and 34. During the first part of the clockwise movement of the operating member 61 and of delivery movement of the two feed rollers 43 and 44 the cam roller 28 rides on the initial cam surface 66 and consequently without movement being imparted to the cam lever 24 and cup-supporting rollers 30 and 34. At an intermediate point of the delivery of the cup after its upper edge or rim has passed below and is free from the rollers 30 and 34, but while the upper edge of this downwardly moving cup is still projecting to a substantial extent above the cooperating gripping surfaces of the feed rollers 43 and 44, the cam roller 28 will be engaged by the inclined cam surface 66a which will rock the left hand rock shaft 23 in a counter-clockwise direction, thereby raising the lifting fingers 29 and 33, the rollers 30 and 34 being moved slightly inward, to increase their pressure upon the cup, and being moved to a greater extent upward, which will lift the entire stack of cups so that the lowermost cup therein will be raised clear and free from the cup which is being delivered. The extent of the cup-lifting movement of these rollers 30 and 34 may be anything found desirable, and in the construction shown in the drawings, these rollers move through an arc of about $\frac{5}{16}$ of an inch and are raised substantially a quarter of an inch.

65 After the stack of cups 1 has been thus

raised by the inclined cam portion 66a, the outer circularly arcuate terminal portion 66b then travels in engagement with the cam roller 28 and holds up the stack of cups until the operating member 61 has completed its forward movement and the cup being fed by the feed rollers 43 and 44 has been released thereby and delivered. At an intermediate point of the reverse or return movement of the rocking operating members 61, the intermediate inclined cam portion 66a again engages with the cam follower roller 28, followed by the engagement with this roller of the circularly arcuate inner cam portion 66 thereby permitting the stack of cups 1 to descend by their own weight, while the feed rollers 43 and 44 are at rest, the stack of cups then being supported upon the rollers 30 and 34 of the lever arms or lifting fingers 29 and 33 with the angular bottom margin of the terminal or lowermost cup 1 then resting lightly upon and between the cup-feeding peripheral surface of the feed rollers 43 and 44 preparatory to the next delivery operation of the machine.

The spring 73 imparts a rather rapid return movement to the operating member 61, together with the reverse or return rotation of the feed roller operating gear 54 along with the released clutch element 56-57, and the momentum of these moving parts is absorbed by the cushion element 79 without jar or noise. Forward stop means are provided for the rocking operating member 61 indirectly through the intermediary of the coil controlled mechanism, which is now to be described.

Some of the parts and features of the above described dispensing mechanism have a co-operating relation with some of the parts and features of the coin controlled mechanism, such as is commonly the case in the operating mechanism of a vending machine.

A coin carrier 85 in the space between the front plate 6 of the casing and the operating member 61 is fixed on the middle portion of the handle shaft 62. The coin carrier may be a zinc die casting with the handle shaft, which may be of steel, cast therein as an insert, while the handle knob 63 may be detachably held upon the outer end of the shaft by means of a set screw (not shown). The coin carrier is in general of somewhat irregular segmental shape, located for the most part to the left of and below the handle shaft 62. At its front side the coin carrier 85 has a tubular stem 86 which extends forward on the handle shaft 62 to the inner side of the hub of the handle knob 63. An outer boss 87 formed on the front of the front plate 6 has a brass bushing 88 fixed therein which forms a bearing for the outer reduced end portion of the coin carrier stem 86.

The front plate 6 has through it a coin slot 89 which is at the left side of, slightly above

and substantially radial to the common axis of the handle shaft 62 and coin carrier 85. A proper coin 90, which in the machine shown is a penny, may be inserted edgewise through the coin slot 89 into a substantially radial coin-holding slot provided on the coin carrier 85, with the outer radial edge portion of this coin projecting from the coin-holding slot beyond the periphery of the coin carrier 85. This coin-holding slot is provided between and is formed by means of lower and upper lugs 91 and 92 which project from the front of the peripheral portion of the coin carrier 85. The lower lug 91 moves the coin 90 while the upper lug 92 holds the coin in position relatively to the lower lug 91. The top of the coin-moving lug 91 is substantially U-shaped, providing radially inner and outer rounded ridges which engage with the coin 90 at opposite sides of its center. The holding lug 92 engages with the coin about from its center outwardly, with a radial edge portion of the coin 90 exposed. The radially inner edge of the coin 90 abuts against and in its movement is guided by the circularly arcuate outer surface of a coin guide 93 which projects inwardly from the front plate 6 and may be cast thereon.

The front face of the coin carrier 85 between the slot-forming lugs 91 and 92 forms a stop for the rear edge of the coin while the forward edge of the coin may move adjacent to and be guided by the inner surface of the front plate 6. The coin guide 93 extends from below the coin-holding slot and lower side of the coin 90 therein, upwardly and to the right above and to the right of the axis of the coin carrier 85 and terminates abruptly in an overhanging radial end which will permit the coin 90 to drop out of the coin-holding slot when it reaches this end of the coin guide and after the coin has traveled through an arc of about 105°. The coin carrier 85 has a slight overthrow beyond this point where the coin 90 passes beyond the abrupt upper end of the coin guide 93 to assure that the coin will be discharged, and the coin carrier may rock through an angle of about 110° for this purpose.

A stop lug 94 for the coin carrier 85, located at the left side of and just below the coin carrier axis, projects from the front plate 6 and may be cast thereon. A lug 95 which projects forward from the lower and right hand end of the coin carrier 85 will abut against the lower side of the stop lug 94 to stop the forward or clockwise movement of the coin carrier, while the lower side of the coin-moving lug 95 will abut against the upper side of this stop lug 94 to stop the return or counter-clockwise movement of the coin carrier with its coin-holding slot then in alignment with and immediately inward from the coin slot 89 in the front plate 6. The coin carrier 85 is automatically returned to this

normal position by means of a coiled torsion spring 96 which surrounds its stem 86, one end of this return spring being secured to the coin carrier by means of a stud 97 while the other end of the spring is anchored under a rib 98 which projects downwardly from the lower end of the coin guide 93.

The periphery of the coin carrier 85 at its front side is provided with a wide forwardly projecting arcuate flange 99 which, radially outward from the stop lug 94, extends from the coin-moving lug 91 around the lower edge of the coin carrier to the coin carrier stop lug 95. The forward edge of this flange 95 is in close proximity to the inner face of the front plate 6, so that while the coin carrier 85 is being operated in its rocking to and fro movement, the coin slot 89 will be closed or blocked by this flange 99 against the insertion of a coin, until the coin carrier has been returned to its normal position.

Should the edge of an inserted coin be left projecting into the coin slot 89 in the front plate 6, it is obvious that the coin carrier 85 would be locked by this coin against movement. In order to prevent this, coin-positioning means are provided to impart final inward movement to the inserted coin and to position the coin properly in the coin carrier between the slot-forming lugs 91 and 92 with the radially inward edge of the coin against the coin guide 93 and with the outer or forward edge of this coin inward from the inner face of the front plate 6 and thus clear of the coin slot 89.

For this purpose a coin-positioning lever 100 (Figs. 8 and 9), which is flat with rounded edges, is pivoted on the inner headed end of a stud 101 on the front plate 6 with this lever close to the inner side of this plate. The pivot stud 101 is located some distance below the outer end of the coin slot 89 with the lever 100 projecting upward across the radially outward end portion only of the coin slot 89. This lever 100 below its pivot stud 101 has a tail arm 102 shown as beveled at its end which abuts against a lug 103 on the front plate 6 to limit the extent to which the lever 100 may pass over or cover the coin slot 89. A two-armed wire spring 104 having a coil on the inner headed end of the pivot stud 101, has the end of one of its arms connected to the lever 100 by a small pin 105 while the end of its other arm, above the pivot stud 101, abuts against a lug 106 on the front plate 6.

This spring 104 normally yieldingly holds the lever 100 with its tail arm 102 abutting against the lug 103 and with its rounded edge portion adjacent to its upper end passing across the radially outer end portion of the coin slot 89 in the front plate 6 (Fig. 9). When a proper coin is pushed inward through the coin slot 89, its rounded edge will push the lever 100 aside, but during the latter part

of the inward movement of this coin, the 5 spring-pressed lever 100 will have an increasing tendency to move the coin inward and will finally move this coin inward clear of the coin slot 89 with its forward edge at the inner side of the front plate 6. It may be noted that a coin-positioning lever operating in substantially the same manner is claimed in my Patent No. 1,657,836 of January 31, 1928.

10 With the rocking operating member 61 at its normal position (Fig. 2) and when the coin carrier 85 carries no coin, the coin carrier may be freely and idly rocked to and fro between its limits of movement or between any intermediate points. When the 15 coin carrier 85 carries a coin 90, this coin itself forms a coupling member which directly engages with a cooperating coupling member on the operating member 61 for moving the latter away from its normal position until the coin has been discharged at the termination of the clockwise part of the to and fro operating movement of the operating member 61. For thus cooperating with the 20 coin 90, to be moved thereby, a stud 107 projects to the front from the wide flange 64 of the operating member 61 and may desirably be a steel insert cast into a thickened 25 portion of the flange 64. This projecting stud is shown as square with two of its opposite corners in radial alignment with the common axis of the operating member 61 and coin carrier 85, so that thereby its flat faces 30 or sides are radially inclined 45°.

35 This stud 107 is located on the operating member 61 at a position so that with this operating member and the coin carrier 85 both at their normal positions (Fig. 2), the outer edge of the inserted coin 90, which projects radially beyond the periphery of the coin carrier, will be in close proximity to and just below and inward from the lower radially inner inclined face of this stud 107, for moving the latter immediately upon 40 movement of the coin carrier 85. This inclined face of the stud 107 will press the opposite edge of the coin 90 against the coin guide 93, so that thereby this inclined face of the stud, acting as a cam, will dislodge 45 the coin from the coin-holding slot in the coin carrier when the coin has been moved beyond the upper end of the coin guide 93. When the coin is discharged by the coin carrier, it will be received upon and will slide 50 down an inclined chute 108, from the lower end of which it will drop into the coin box at the inner side of the front door 13. This coin chute 108 may be cast upon the front plate 6 and at its upper edge is notched around the adjacent peripheral parts of the operating member 61 and coin carrier 85 (Figs. 2, 8 and 9).

55 An undersized slug, the diameter of which is less than the distance between the radially

inner corner of the operating stud 107 and the guiding surface of the coin guide 93, will not operate the delivery mechanism of the machine. If such a slug should engage with the stud 107 it will be pushed aside by the 70 inclined cam face of this stud and will be discarded by the coin carrier 85 when the slug passes beyond the upper end of the coin guide 93. In order to make it more certain that such a small sized slug will be discarded with a single movement of the coin carrier, means are provided to prevent return movement of the coin carrier from a partially advanced position when it carries such a slug. 75

80 For this purpose an arcuate ratchet member 109 is mounted in a deep slot in the outer or guiding surface of the coin guide 93, substantially flush therewith, and is pivoted intermediate of its length on a pivot pin 110 85 which forms a rivet passing through the coin guide 93 and the front plate 6 (Figs. 2, 8 and 9). This ratchet member 109 has ratchet teeth, shown as three in number, projecting above the upper portion of the coin guide 93 90 and inclined towards its adjacent upper end. This toothed end of the ratchet member 109 is urged upwardly by means of a small coiled compression spring 111 which is seated in a recess in the bottom of the slot in the coin guide 93 below this end of the ratchet member 109, the depending tail arm of this ratchet pawl 109 serving as a stop against the bottom of the slot in the coin guide 93. 95

100 As soon as an undersized slug has passed over and been engaged by the first ratchet tooth it encounters, then reverse or return movement of the coin carrier is thereby prevented and it is necessary that the coin carrier must be fully advanced for discarding this slug before the coin carrier can be returned to its normal position preparatory to the insertion of a proper coin in its coin-holding slot, which has been freed from the slug which would block the insertion of a coin. 105

110 The upper end of the coin carrier 85 is provided with a peripheral and, as a whole, substantially radial tapering projection or lug 112 having a lower radially inclined face which is normally in engagement with or abuts against the upper and radially inner inclined face of the operating stud 107 (Fig. 2). It will be noted that this projection 112, in engagement with the upper side of the stud 107, and the coin 90 in engagement with the lower side of this stud, will lock or couple the operating member 61 and the coin carrier 85 together against movement relatively to each other in either direction. Also the coin 90 is locked by the stud 107 in the coin-holding slot of the coin carrier against possibility of escape therefrom until it has been discharged at the upper end of the coin guide 93. 115

120 This projection 112 on the coin carrier 85 130

by its engagement with the operating stud 107 prevents return movement of the coin carrier 85 independently of the operating member 61 when the latter has been moved 5 away from its normal position, and this assures that the coin 90 will be kept locked in the coin-holding slot of the coin carrier. The operating member 61 of course can only be moved forward by means of a coin carried 10 by the coin carrier 85 and when this operating member has been moved forward or clockwise only a short distance, it will be locked against return movement by the locking pawl 67, as hereinbefore set forth. Re- 15 turn movement of the coin carrier 85 from a partially advanced position is not then permitted, since that would move the coin away from the operating stud 107, so that to and fro movement of the coin carrier under such 20 conditions would be likely to throw the coin out of or dislodge it from the coin-holding slot of the coin carrier and the coin would then be lost in the machine.

Some further note may be taken of the 25 manner of operation of the mechanism as so far described. It will be noted that the peripherally projecting coin carrier lug 112, in cooperation with the operating stud 107 directly, together with the cooperating coin 30 carrier stop lugs 94 and 95 indirectly, forms a stop for limiting the forward or clockwise movement of the operating member 61. This prevents overthrow of the operating 35 member 61, such as might cause the cam roller 28 to run off the trailing end of the terminal cam surface 66b, as well as otherwise disarrange the operating mechanism.

It will be also noted that this operating 40 stud 107, against which the coin carrier projection 112 abuts, may serve as a return stop for the coin carrier 85, through the intermediary of the return stops 78 and 79 for the operating member 61. However, it is 45 desirable to provide a separate return stop for the coin carrier 85, as hereinbefore described, in order to assure that the coin-holding slot of the coin carrier will be brought correctly into alignment with the coin slot 89 in the front plate 6. It will be 50 further noted that the coin carrier return spring 96, acting through the intermediary of the peripheral coin carrier lug 112 and the operating stud 107, would also be effective alone to return the operating member 61 to 55 its normal position.

An advantage of the separate return spring 73 for the operating member 61 is that it permits a lighter spring to be employed for returning the coin carrier 85, in view of the 60 fact that the coin carrier is separately operated many times idly, as well as also for discarding slugs, which may be not only small slugs as above noted but also frail slugs such as of paper or of thin metal, which 65 will be bent and discarded without oper-

ating the member 61. Another advantage of the separate spring 73 is that it cooperates with the inclined coin-engaging cam face of the operating stud 107 in dislodging the coin from the coin-holding slot in the coin carrier 85 when the coin has passed the upper end of the coin guide 93 by which the coin 90 is maintained in operating engagement with this inclined cam face of the operating stud 107.

For operating the machine shown as a dispensing device without need of inserting a coin, should that be desired in some installations, it is only necessary to drive a sufficiently thick lug between the coin carrying lugs 91 and 92 of the coin carrier, to project into operating engagement with the operating stud 107, and at its other end to pass above or clear the ratchet teeth of the slug ratchet 109. Or on the other hand, if desired, the coin carrier 85, together with the other parts of the coin controlled mechanism per se, may be omitted, the operating member 61 then being fixed upon the handle shaft 62 and provided with a separate forward stop, which it is obvious may be readily done in several very simple ways, for example, by attaching a lug to the front face of the casing wall 5 to be in the path of the shoulder shown on the operating member 61 at the leading end of its cam surface 66 and ratchet 72.

When the stack of cups 1 in the magazine tube 2 requires replenishing the coin carrier 85 is automatically locked at a forward position in which its front flange 99 closes the coin slot 89 in the front plate 6 against the insertion of a coin, thereby to prevent the loss of coins in the machine. For accomplishing this, an upstanding feeler lever 113 is 100 pivoted by means of a pin 114 between a pair of lugs on the back of the front top bracket 11 (Fig. 2 and 3). The feeler lever 113 at its upper free end, has an inwardly tapering rounded feeler projection 115 to engage with the stack of nested cups 1, while not interfering with their free downward movement, nor with the lifting of the stack of cups in the operation of the machine, nor with the insertion of a fresh stack of cups into the 115 magazine tube 2.

The feeler lever 113 has a downwardly extending locking arm 116 forming a locking pawl which at its lower end is provided with a forwardly projecting locking end 117, the 120 upper end of the wall of the front casing part 5 being provided with a vertical slot as shown in Figs. 2 and 3 for the accommodation of this locking arm 116 and its locking end 117. The two arms 113 and 116 of the combined feeler lever and locking lever are disposed at a slight angle to each other, so that the most of the weight of both of these arms is at the rear of the pivot 114, so that this lever as a 125 whole has a normal tendency to swing by 130

gravity in a clockwise direction as viewed in Fig. 3. Thus the feeler end 115 of the feeler lever 113 will be pressed lightly by gravity against the upper edge portion of the telescoped cups 1 in the stack in the position of this lever which appears in Fig. 3, in which, however, the stack of cups has been omitted for clarity of illustration, excepting the lowermost cup which is shown in broken lines. In this position of the feeler lever 113 its locking end 117 will be in withdrawn position at the rear of the upper margin of the path of movement of the operating member 61, so that the latter may be rocked freely back and forth clear of this locking end.

On its back the wide flange 64 of the operating member 61 is provided with a locking lug 118, which forms the above noted thickened portion in which the inner end of the operating stud 107 is fixed (Figs. 2, 10 and 11). The advancing or forward end of this lug 118, as the operating member 61 moves in the clockwise direction, forms an inclined cam face 119 while the other or trailing end of this lug forms an abrupt shoulder 120. When the upper edge or rim of the uppermost or last cup 1 in the stack descends below the lower surface of the feeler end 115 of the feeler lever 113, this lever will be rocked by gravity to move its locking end 117 into the path of movement of this locking lug 118. The inclined cam face 119 of this lug will ride past this locking lever end 117, but soon after the operating member 61 begins its return movement the shoulder 120 will abut against the locking end 117, thereby stopping the return movement of the operating member 61, which will take place at an advanced position of about 90° from the normal position thereof shown in Fig. 2.

When the operating member 61 is thus locked against further return movement, the coin carrier 85 will also be locked against further return movement by its peripheral-45ly projecting lug 112 abutting against the operating stub 107 on this operating member 61. In this locked position of the coin carrier 85, its front flange 99 will extend across or close the coin slot 89 in the front plate 6, thereby preventing the insertion of a coin through this slot. Should it be desired to arrange or adapt the machine shown to operate as a dispensing device without using a coin, as hereinbefore noted, the feeler 50 lever 113 may be retained in toto, or this feeler lever may be omitted, that being substantially immaterial.

It is obvious that various modifications may be made in the construction shown in 60 the drawings and above particularly described, within the principle and scope of the invention as defined in the appended claims.

I claim:

65 1. In a vending machine, the combination

of an outer casing wall provided with a coin slot for the edgewise insertion of a proper coin, a rocking coin carrier immediately inward from the said wall pivoted on an axis at right angles thereto and provided with a transverse coin-holding slot which is normally in alignment with said coin slot immediately inward therefrom for moving the coin flatwise adjacent to said wall and so that when the coin carrier is operated the portion thereof adjacent to its coin-holding slot closes said coin slot in the casing against the insertion of a coin, a rocking operating member coaxial with and immediately inward from the coin carrier to be coupled thereto to be operated thereby by means of a coin carried by the coin carrier, an abutment on the operating member engageable with the coin carrier to prevent independent return movement of the coin carrier when the operating member is moved by the coin, a magazine for a supply of articles to be vended, vending mechanism to be operated by the said operating member, a normally disengaged lock to be engaged with the said operating member at its coin-operated position, and operating means for the lock controlled by the supply of articles to lock the operating member at its coin-operated position for thereby locking the coin carrier at slot-closing position when the magazine needs replenishing.

2. The invention defined in claim 1, in which the means for operating the said lock includes a feeler urged against successive articles transversely to their direction of movement and the lock being controlled by the feeler to be moved to its locking position to prevent the insertion of a coin when there is no article in position to restrain the feeler.

3. In a coin controlled mechanism, the combination of a coin carrier pivoted for rocking to and fro movement, a normally idle operating member the movements of which are to be utilized pivoted for rocking to and fro movement coaxially with the coin carrier, means on the coin carrier for moving a coin and on the operating member to be engaged by the coin by which the coin carrier operates the operating member away from its normal position and then discharges the coin, interengaging means between the operating member and the coin carrier by which the coin carrier is prevented from returning to its normal position independently of the operating member, and a double acting reversible pawl-and-ratchet device for the operating member which prevents return movement of the operating member to its normal position until its movement away from its normal position has been substantially completed and thereby also prevents return movement of the coin carrier by reason of the said interengaging means.

4. In a coin controlled mechanism, the com-

bination of a coin carrier pivoted for rocking to and fro movement, an operating member the movements of which are to be utilized pivoted for rocking to and fro movement 5 coaxially with the coin carrier, the coin carrier being freely movable away from its normal position independently of the operating member, a lug on the operating member to be engaged by a coin carried by the coin carrier 10 for moving the operating member away from its normal position by means of the coin carrier, a projection on the coin carrier to engage with the said lug to prevent return movement of the coin carrier independently 15 of the operating member when the latter has been moved away from its normal position, a double acting reversible pawl-and-ratchet device cooperating with the operating member to prevent return movement of the latter 20 until after it has completed the extent of its coin-operated movement thereby also at the same time preventing return movement of the coin carrier, a stop for limiting the extent of movement of the coin carrier away from 25 its normal position which thereby also limits the same movement of the operating member, means for discharging the coin from the coin carrier at the limit of its advancing movement, a return stop for the operating member 30 which thereby also prevents further return movement of the coin carrier, a return spring for the coin carrier by which the operating member is also returned, and an operating handle connected to the coin carrier for advancing the latter against the tension of its 35 spring.

5. The invention defined in claim 4, in combination with a cushion shock absorbing member forming one element of the said return stop for the said operating member, a separate return stop for the coin carrier, and a separate return spring for the operating member so that thereby the latter may be returned to its normal position independently 45 of the return movement of the coin carrier.

6. In a coin controlled mechanism, the combination of a coin carrier pivoted for rocking to and fro movement, a casing wall just at the front of the coin carrier provided with 50 a coin slot at one side laterally of the axis of the coin carrier, a pair of lugs on the coin carrier forming between them a coin-holding slot which in the normal returned position of the coin carrier is in alignment with the 55 said coin slot in the casing wall, an arcuate coin guide on the casing wall for the radially inner edge of the coin extending from the coin slot in the casing wall on a convex curve upwardly and laterally to a point above the 60 axis of the coin carrier and there terminating abruptly to permit the coin to drop out of the coin-holding slot in the coin carrier when it has passed this upper end of the coin guide, an operating member pivoted for rocking to 65 and fro movement immediately inward from

the coin carrier and coaxial therewith, and a forwardly projecting stud on the operating member having a radially inclined face to be engaged by the radially outer edge of the coin so that thereby the pressure of the coin 70 against this inclined face of the stud will dislodge the coin from the coin-holding slot in the coin carrier when the coin has been moved beyond the said upper end of the coin guide.

7. The invention defined in claim 6, in combination with an upwardly spring-pressed ratchet member having ratchet teeth projecting above the upper portion of the coin guide and inclined towards its upper end so as to permit the advance of either a proper coin or a slug carried by the coin carrier and preventing return movement of the coin carrier when it carries an undersized slug the diameter of which is too small to engage with the 80 said stud of the operating member so that thereby the coin carrier must be fully advanced for discarding such slug before it can be returned to its normal position preparatory to the insertion of a proper coin in its 85 coin-holding slot.

8. The invention defined in claim 6, in combination with engaging means between the said operating member and the coin carrier to prevent return movement of the coin carrier 90 relatively to the operating member so that thereby the coin will be locked in position in the coin-holding slot of the coin carrier by the said inclined face of the stud on the operating member.

9. The invention defined in claim 6, in combination with engaging means between the said operating member and the coin carrier to prevent return movement of the coin carrier 95 relatively to the operating member so that thereby the coin will be locked in position in the coin-holding slot of the coin carrier by the said inclined face of the stud on the operating member, and a pawl-and-ratchet device for the operating member to prevent return movement of the latter until after 100 it has completed its coin-operated movement.

10. In a coin controlled mechanism, the combination of a coin carrier pivoted for rocking to and fro movement, an operating member the movements of which are to be utilized pivoted for rocking to and fro movement coaxially with the coin carrier, the coin carrier being freely movable away from its normal position independently of the operating member, means by which the said operating member may be coupled to the coin carrier to be operated thereby by the coin carrier, a stop on the coin carrier to be engaged by the said operating member to prevent overthrow of the latter in its coin-operated movement, a stop for limiting the extent of movement of the coin carrier away from its normal position which thereby also limits the same movement of the operating member, a return 115

- stop for the operating member which by reason of the said stop on the coin carrier may be also utilized to prevent further return movement of the coin carrier, a return spring for the coin carrier by which the operating member may also be returned, and an operating handle connected to the coin carrier for advancing the latter against the tension of its spring.
- 10 11. The invention defined in claim 10, in combination with a separate return stop for the coin carrier in addition to the said stop provided on the coin carrier, and a separate return spring for the operating member in 15 addition to the said coin carrier spring.

LOUIS H. MORIN.
